UNITED STATES PATENT OFFICE

GEORGE I. STANFORD, OF MILFORD, CONNECTICUT, ASSIGNOR TO THE UNIVERSAL PIPE AND RADIATOR COMPANY, OF NEW YORK, N. Y., A CORPORATION OF MARYLAND

SHEET METAL RADIATOR

Application filed January 31, 1930. Serial No. 424,842.

This invention relates to steam or other radiators which as ordinarily constructed for heating the interior of buildings are made of cast metal. The object of the invention in general is to make it possible to use sheet metal in the construction of the radiator in such manner as to secure the advantages of cheapness, small weight, high radiating effect with a comparatively small size of radiator and other advantages which will be apparent to those skilled in the art from the following description.

The invention relates more particularly to certain improvements in the construction of a radiator comprising a relatively large and unobstructed heat or steam chamber made up of sheet metal which may have flat or plane front and rear walls combined with exterior members of corrugated sheet metal secured to one or both of said walls and having plane surfaces at the elbows or bends thereof fastened directly against the surfaces of the walls in heat conducting relation thereto, said member or members being applied in position such that the axes of the corrugations extend vertically over the walls of the sheet metal steam chamber and to provide vertical sheet metal ducts which confine the air and induce circulation vertically from the bottom to the top thereof, thereby conducting to the efficient absorption of heat from the chamber and rapid heating of the air thus caused to circulate naturally through said vertical ducts. In carrying out the invention it is proposed to employ by preference aluminum or other non-rustable metal, although ordinary sheet steel or sheet iron may be used, and provided with a suitable surface finish.

One of the objects of the invention is to provide a simple and cheap construction of steam chamber which will contain a substantial quantity of steam and permit the same to pass readily through the chamber and to combine with this chamber an effective heat absorbing construction which will rapidly absorb the heat from the steam or vapor during the brief time the steam remains in the chamber.

A further object of the invention is to ob-

tain in a radiator constructed from sheet metal in the manner hereinbefore set forth a highly ornamental effect together with strength due to the manner of construction and with an added heat-radiating capacity thus permitting the use of light sheet metal with attendant cheapness in the manufacture of the radiator.

This part of the invention consists in providing a multiplicity of horizontal strengthening strips of metal spaced apart and crossing the corrugations horizontally and welded or otherwise secured in direct contact to the exterior bends of the corrugated member and which, while adding to the ornamental appearance, also conduct to rapid and efficient radiation of the heat of the contents of the chamber containing the steam or other heat medium.

The invention consists further in the details of construction and combination of parts hereinafter more particularly described and then specified in the claims.

Fig. 1 is a perspective view of one form of the radiator embodying the invention.

Fig. 2 is a vertical section through the same on the line 2—2 of Fig. 1.

Fig. 3 is a perspective view of a part of one of the end portions of the radiator chamber.

The body of the radiator is shown as formed of sheet metal and includes the front wall 1, the rear wall 1', the top wall 2, and bottom wall 2' of an upright steam chamber a. This sheet metal body can be conveniently made by bending up a piece of sheet metal of the proper length into the form required and lapping its free ends as indicated at 3, Fig. 2, where said ends are fastened or secured together in any suitable way so that the chamber will be air or steam-tight at this point. To complete the steam chamber, the end members 4 are employed, these members being indicated in perspective in Fig. 3. The end members 4 may be formed so that they can be inserted into the body and can be secured therein by the flanges 4' in a suitable steam and air-tight joint. They might be made in other forms to complete the steam chamber. Each of them is pro-

vided with the usual outlet or fitting F as shown in Fig. 1.

Secured in vertical position against the front wall 1 is a corrugated member 5 which may be made of thin sheet metal. The bends or elbows 5' between the projecting members of said corrugated member are made of such shape that they will lie flat against the surface of the wall and thereby efficiently absorb heat by conduction from said wall. It is preferred to weld the flat surface 5' at intervals, as at 9, to the wall of the steam chamber so that the heat will be more readily conducted from the steam chamber to the heat-radiating members or vanes. It will be obvious however that they may be soldered, welded or otherwise fastened in position. The whole corrugated member is disposed as shown with the axes of the corrugations in vertical position. The corrugations form in effect a series of heat-radiating fins or vanes.

By this disposition it will be seen that closed vertical air ducts are provided upon the face of the front member 1 and that a forced natural circulation of air will take place from the bottom through each of said ducts and out of the top and in so doing the air will take up heat not only from the side portions of the corrugations which acquire heat through the flattened part 5' but also from the portion of the front wall of the steam chamber which forms the inner wall of the air ducts.

If desired a similar corrugated member 35 may be fastened against the rear wall 1' of the sheet metal steam chamber. If the installation will permit I prefer to employ the corrugated member, disposed as described, to both front and rear walls in order to secure the greatest radiating efficiency but my invention is particularly applicable where only one wall of the radiator will be exposed in which case the surface members will be omitted from the wall not available and the heat concentrated on the other wall.

Secured in horizontal position and extending transversely across the outer elbows or bends of the corrugated member are metal strips 7. As many of these may be employed as desired. They are also preferably made of sheet metal and may be welded at all or a portion of the points of engagement of the strips against the outer edge of the members 5. When so employed the members 7 have the function not only of adding to the appearance of the radiator but of assisting in radiating heat conducted from a wall of the chamber through the sides of each corrugated portion of the corrugated member and of increasing the strength of the radiator by supporting the outer edges of the members 5.

The upper longitudinal member 7 may extend over the end of the corrugated member and be secured to the edges of said corrugated sheet by welding or otherwise to further

strengthen the structure of the radiator. This is particularly desirable inasmuch as it permits the use of a very light gage of sheet metal for the corrugated member thereby lessening greatly the cost of material.

The transversely extending portion 7' of the upper strip 7 may be extended over into contact with the upper wall 2 of the steam chamber and be fastened thereto for adding to the strength and further assisting in the conduction and radiation of heat. The transverse portion 7' of said upper member 7, when this particular form of member 7 is employed, is provided with openings as shown to permit the egress of the air passing upwardly through the air ducts and heated in its passage as set forth.

The bottom strip 8 may be similarly constructed as a reinforcing member extending along the outer face of the lower edge of the sheet metal member and extending inwardly beneath member 5 as illustrated. It is preferable that this member should extend only a slight distance over said free edge in order that air may enter freely at the bottom and circulate up through the ducts 1 and the spaces between the projected portions of the corrugated member.

Any suitable support may be employed for supporting the radiator above the floor so that air shall have free access to the lower ends of the ducts. For example the lower strips 8 may each be formed with a series of spaced fingers extending downwardly and struck out from the metal of the members 8 for supporting the radiator.

By the use of my invention the radiator may be made entirely of sheet metal and a high degree of radiating effect secured by reason of the construction of the elements and their relation to one another as already described. The relatively large and open steam or vapor chamber will offer little obstruction to the passage of steam therethrough and the surface construction will rapidly absorb the heat from the steam chamber and discharge it into the room. Thus a radiator of great cheapness and of comparatively small dimensions may be produced as compared to the usual cast metal radiators.

What I claim as my invention is:

1. A radiator comprising a heat-radiating chamber made up of a piece of sheet metal bent to provide a bottom, top, front and rear wall, the ends of the metal sheet being lapped and joined in the top wall and said chamber being completed by flanged end members secured by their flanges in the openings in the bent portion and furnished with the usual outlets or fixtures, all combined with a corrugated sheet metal member fastened at the elbows or bends thereof directly against the front of the sheet metal chamber and affording, by the vertical disposition of the axes of the corrugations, air ducts for circulation of

the air in a vertical direction in contact with the corrugations and with the wall of the chamber.

2. A radiator comprising a heat or steam chamber constructed from sheet metal, heat-radiating corrugated sheet metal formed with flattened faces secured directly against the outer surface of the sheet metal body, combined with a multiplicity of cross strips 5 of sheet metal spaced apart and suitably fastened across the outer bends of the corrugated member to permit the use of exceedingly light gage sheet metal for said corrugated member, the upper one of said strips including a portion turning inwardly and secured directly to the edge of said corrugated sheet metal member to secure further rigidity.

3. A radiator comprising a heat or steam chamber constructed from sheet metal, heat-radiating corrugated sheet metal formed with flattened faces secured directly against the outer surface of the sheet metal body, combined with cross strips of sheet metal 10 suitably fastened across the outer bends of the corrugated member to permit the use of light gage sheet metal for said corrugated member, an end one of said crossing strips turning inwardly and being continued across the edge of the corrugations to connect with 15 the upper wall of the sheet metal steam chamber.

30

Signed at New York in the county of New York and State of New York this 29th day of January, A. D. 1930.
